UNITED STATES PATENT OFFICE.

DANIEL APPEL, OF CLEVELAND, OHIO, ASSIGNOR TO THE UNION PAPER BAG MACHINE COMPANY, OF PHILADELPHIA, PENNSYLVANIA.

FOLDING-MACHINE.

SPECIFICATION forming part of Letters Patent No. 340,080, dated April 20, 1886.

Application filed September 11, 1885. Serial No. 176,777. (No model.)

To all whom it may concern:

Be it known that I, DANIEL APPEL, a citizen of the United States, residing at Cleveland, county of Cuyahoga, and State of Ohio, have 5 invented certain new and useful Improvements in Folding-Machines, fully described and represented in the following specification and the accompanying drawings, forming a part of the same.

10 This invention relates to a folding mechanism which is capacitated to impart three parallel transverse folds, said mechanism being adapted to operate upon a continuous web to sever the same into sheets of the proper length, 15 and then fold the sheets asstated, or to operate upon detached sheets fed to it by hand or otherwise.

The mechanism constituting the present invention can be employed in any case where it 20 is desired to impart three parallel transverse folds to a web or sheet, but is especially adapted to impart the three parallel folds necessary in the formation of paper bags having bellows or infolded bottoms—such, for example, as the 25 bag shown in United States Letters Patent No. 155,610 or No. 296,117.

The invention is therefore in the present case shown as embodied in a mechanism of suitable form for folding the bottoms of bellows-bottomed bags.

30 As a full understanding of the invention can be best imparted by a detailed description of the construction and operation of the mechanism in which it is embodied, all further preliminary description will be omitted and a full 35 description given, reference being had to the accompanying drawings, in which—

Figure 1 is an end elevation of a mechanism embodying the invention in a form capable of 40 operating upon a continuous web to sever the same into short lengths or bag-blanks and impart thereto the three parallel transverse folds for the formation of the bellows-bottom. Fig. 2 is a side elevation of the same, parts being 45 broken away to expose the mechanism for operating the severing-blade and one of the tucking-blades. Figs. 3 to 6 are cross-sections of the cutting and folding rolls, showing the parts in different positions, to illustrate the operation of the mechanism. Fig. 7 is a side elevation 50 of the folding mechanism when construct-

ed to operate only upon detached blanks. Fig. 8 is a plan view of the same. Figs. 9 to 13 are cross-sections of the folding-rolls, showing the parts in different positions, to illustrate 55 the operation of the mechanism; and Figs. 14 and 15 are diagrams which will be hereinafter referred to.

Referring now particularly to Figs. 1 and 2, it is to be understood that the folding mechanism therein shown consists, primarily, of four rolls or cylinders, A B C D, which are supported in a suitable frame-work, and are provided with engaging gears *a b c d*, by which they are caused to turn in unison and in the 60 direction indicated by the arrows in Fig. 2. These rolls are arranged so that their axes occupy nearly the four corners of a square and so as to form three co-operating pairs, the rolls A B forming one pair, the rolls B C another 70 pair, and the rolls C D another pair. The rolls A D are, however, separated a short distance, as will be observed, so that they do not co-operate directly.

The roll A is provided with a tucking-blade, 75 9, and a severing-blade, 8, which blades are located in recesses 12, formed in the roll, and are secured at their ends, which project beyond the ends of the rolls to a pair of heads, 10, which are mounted upon a rock-shaft, 11, 80 journaled in the roll or upon studs extending from the ends of the roll, so as to be capable of oscillating freely to project the blades beyond or retract them within the periphery of the roll. One of the heads 10 is provided with a 85 yoke, 13, which embraces an eccentric, 14, formed on the hub of a gear, 15, which is mounted to turn freely on the shaft 16 of the roll A, and is engaged by a gear, 17, fixed on the shaft of the roll B. The gear 17 is of one-half the size of the gear 15, from which it results that the eccentric 14 is caused to make only one revolution to each two revolutions of the rolls, thereby rocking the yoke 13 and heads 10 in one direction on one revolution of the rolls and in the opposite direction on the next revolution. This causes the blades 8 9 to be projected and retracted at alternate revolutions of the rolls, and also to alternate with each other.

The roll B is provided with a cutting-groove, 7, which is so positioned as to co-operate with

the blade 8 to sever the web, in the usual manner, whenever the blade is projected so as to enter the groove. The roll B is also provided with a groove, 6, which is so positioned as to 5 co-operate with the blade 9 and receive the fold-line of the paper whenever the blade is projected so as to enter the groove. The groove 6, instead of being formed directly in the periphery of the roll, will preferably be 10 formed in a piece, 5, of rubber or other slightly yielding material, set into the roll, as shown.

The roll C, like the roll B, is provided with a groove, 2, formed in a piece, 3, set into the 15 roll, and the roll D is provided with a co-operating tucking-blade, 4, similar to the blade 9, except that it is fixed in the roll so as to always remain in its projected position.

The roll D, which simply forms a carrier 20 for the blade 4, is cut away, except at its ends, so as to be out of nipping contact with the roll C. In fact the blade 4, instead of being carried by a roll, may be carried upon a pair of disks or arms secured to the shaft 18.

25 The rolls A, B and C D are so timed with relation to each other that the blade 9 and groove 6 and the blade 4 and groove 2 will come into position to co-operate with each other simultaneously.

30 The operation of the mechanism thus constructed is as follows: The web 20, led from the roll E or from any other source, will have its leading end entered between the rolls A, B, just in the rear of the blade 8, upon the revolution of the rolls, when the blade is in its projected position. If the bag to be produced is to be of the character shown in the Letters Patent No. 296,117, the edges of the web will have been previously folded inward to the proper 35 extent, while, if the bag to be produced is to be of the character shown in the Letters Patent No. 155,610, the web will be entered between the rolls in a flat condition. In either case the edges of the web will be provided with suitable lines of paste for forming the side seams of the bag and the roll A; or, if necessary, the rolls A, B C may be provided with circumferential grooves to prevent the roll or rolls from coming into contact with and becoming 40 smeared by the paste. As the rolls A, B continue their revolution, the tucking-blade 9 and the groove 6 will come into position to co-operate, as shown in Figs. 2 and 3; but the blade, being at this time in its retracted position, 45 will not enter the groove, and the end of the web will consequently continue to be advanced by the rolls, and will pass downward in the space between the rolls C D. When the rolls have completed their first revolution, and 50 brought the blade 8 and groove 7 into position to co-operate, the eccentric 14 will have completed one-half a revolution and have rocked the yoke 13 and heads 10, so as to retract the blade 8 and project the blade 9, so that when 55 the blade 9 and groove 6 again come into position to co-operate, the blade will tuck the web into the groove, as shown in Fig. 4, and at the

same time that this takes place the blade 4, which has also come into position to operate, will tuck the web into the groove 2, as also 70 shown in said figure. As the rolls continue their revolution, the portions of the web tucked into the grooves 6 2 will be carried around upon the rolls B C, as shown in Fig. 6, thus making the two transverse folds m n, as shown 75 in Fig. 14. As the rolls continue their revolution from this point, the portion of the web between the folds m n will pass between the rolls B C and be folded at its center, thus making the third transverse fold, o, and forming 80 the bag bottom. When the rolls have completed their second revolution from the point of starting, the eccentric 14 will have completed its first revolution, so that when the blade 8 and groove 7 again come into position 85 to co-operate the blade will be again projected, so as to enter the groove and sever the first bag-length from the web, after which the freshly-cut end of the web will be fed forward by the rolls A B and pass downward between the 90 rolls C D, and the operation will be repeated.

From the foregoing it will be observed that the distance from the leading end of the web to the fold m is just equal to the circumference of one of the rolls less the distance between 95 the blades 8 9, and that the distance from the fold n to the point of severance is the same, from which it results that the sides p q of the bag are of equal length, as shown in Fig. 14.

If it should be desired to operate upon detached sheets or bag-blanks, instead of upon a continuous web, the sheets will be fed to the apparatus so that their leading ends will enter between the rolls A, B, just in the rear of the blade 8, when said blade is in its projected 105 position; or the blade 8 may be omitted, the sheets being fed to the apparatus so that their leading ends will enter between the rolls at the proper point and time.

Figs. 7 to 13 illustrate an organization of 110 the apparatus which is especially adapted to operate upon detached sheets or blanks. In this case the blade 9 is made stationary in the roll A, the same as the blade 4, and the apparatus is provided with a suitably-arranged 115 feed-table, F, and with a series of guides or fingers, 25, for guiding the ends of the sheets therefrom into the bite of the rolls A, B.

The operation of the apparatus, when organized in this manner, is substantially the same 120 as already described. The sheet or blank fed from the table F has its leading end entered into the bite of the rolls A, B at the proper distance (the distance depending upon the length of the sheet or blank) in the rear of the 125 blade 9, as shown in Fig. 9, after which it is fed between the rolls C D, as shown in Fig. 10. As the blades 9 4 come into operation, the blank is tucked into the grooves 6 2, as shown in Fig. 7, after which the two fold-lines are carried toward each other and brought together, and the folding completed 130 by the rolls B C, as shown in Figs. 11, 12, and 13.

By making the rolls A B C D of proper size with relation to the length of the sheet, the distance between the blades 9 4, when they are in the position shown in Figs. 4 and 7, and 5 consequently the distance between the folds $m\ n$, may be made equal to one-half the length of the sheet, thus causing the fold o to be at the middle of the length of the sheet, and the folds $m\ n$ half-way between the fold o and the 10 ends of the sheet, as shown in Fig. 15. When the apparatus is thus organized, it will be well adapted for folding newspapers and other printed sheets.

In conclusion, it is to be remarked that the 15 details of the apparatus hereinbefore described may be varied considerably without departing from the essential features of the invention.

In the organization shown in Figs. 1 to 6 20 the tucking and severing blades 8 9, instead of being operated by an eccentric, may be operated by a cam or cams or by any other means suitable for the purpose. So, also, the tucking blade 4, instead of being stationary in its 25 carrier, may be made movable, if preferred. Although the simple grooves 2 6, particularly if they are formed in elastic pieces set into the rolls, will in most cases be found sufficient to retain the fold-lines of the paper and cause 30 it to be carried around with the roll B C, yet if in any case it should be found necessary or desirable to cause the rolls to take a more positive hold upon the paper, they may be provided in place of the grooves 35 with nipping jaws, into the bite of which the paper will be tucked by the blades 4 9. Such jaws may be of any of the well-known forms, and are to be considered as the equivalent of the grooves for this purpose; or the rolls B C 40 may be provided with sheet-holding pins arranged to impale the paper upon the fold-lines, and cause it to be carried around upon the rolls. In such case the blades 4 9 would be omitted, and the rolls or carriers A D would 45 be arranged so as to simply present or hold the paper in position to be taken by the pins, and such an arrangement of impaling pins is also to be considered as the equivalent of the grooves for this purpose.

50 When a continuous web is operated upon, the severing of the web into sheets or blanks may be effected before it enters between the rolls A B, and in such case the roll A would not be provided with the blade 8. The feeding forward of the sheet, instead of being effected by the rolls A B, may be effected by suitable feeding mechanism arranged to act

upon the web or sheet before it arrives at these rolls. In such case the roll A would simply serve as a carrier for the blade 9 or the blades 6c 8 9, and might be cut away, so as to not run in nipping-contact with the roll B, or the blade or blades might be carried by a pair of disks or arms mounted upon the shaft 16.

The rolls B C may be provided with suitable tapes or cords, arranged in the common and well-known manner, to strip the folded portions $m\ n$ out of the grooves 2 6 or the jaws, or from the pins, and conduct the product away from the rolls; or stationary stripping-fingers, the ends of which rest in circumferential grooves formed in the rolls, may be provided for this purpose.

What I claim is—

1. The combination, with the rolls B C, provided with devices for taking and holding the web or sheet upon the fold-lines $m\ n$, of the rolls or carriers A D, equipped to present the web or sheet in position to be taken by the holding devices upon the rolls A C, all substantially as described. 75

2. The combination, with the rolls B C, provided with means for taking and holding the web or sheet upon the fold-lines $m\ n$, of the rolls or carriers A D, provided with the tucking-blades 4 9, all substantially as described. 85

3. The combination, with the rolls B C, provided with means for taking and holding the web or sheet upon the fold-lines $m\ n$, of the rolls or carriers A D, provided with the tucking-blades 4 9 and the severing-blade 8, all substantially as described. 90

4. The combination, with the rolls B C, having the grooves 2 6, of the rolls or carriers A D, having the tucking-blades 4 9, all substantially as described. 95

5. The combination, with the rolls B C, having the grooves 2 6, of the rolls or carriers A D, having the tucking-blades 4 9 and the severing-blade 8, all substantially as described. 100

6. The combination, with the rolls B C, provided with means for taking and holding the web or sheet upon the fold-lines $m\ n$, of the roll or carrier A, having the moving tucking-blade 9 and severing-blade, and the roll or carrier D, having the tucking-blade 4, all substantially as described. 105

In testimony whereof I have hereunto set my hand in the presence of two subscribing witnesses.

DANIEL APPEL.
